UNITED STATES PATENT OFFICE.

WALTER J. COOMBS, OF QUINCY, MASSACHUSETTS, ASSIGNOR TO
TUBULAR RIVET & STUD COMPANY, OF BOSTON, MASSACHU-
SETTS, A CORPORATION OF MASSACHUSETTS.

LACING HOOK OR STUD SETTING MACHINE.

No. 826,479.

Specification of Letters Patent.

Patented July 17, 1906.

Application filed November 14, 1904. Serial No. 232,727.

To all whom it may concern:

Be it known that I, WALTER J. COOMBS, of Quincy, in the county of Norfolk and State of Massachusetts, have invented certain new and useful Improvements in Lacing Hook or Stud Setting Machines, of which the following is a specification.

The invention relates to machines for setting lacing hooks or studs in shoe-uppers, and more especially to means for insuring the removal of a set stud from the setting devices immediately after the setting operation, so that it shall not interfere with the presenting of the next succeeding hook or stud to the setting devices when running the machine at a high rate of speed.

In setting hooks or studs upon shoe-uppers it is the usual practice for the operator to hold the upper in position to receive the hook or stud and to move the upper forward after each setting operation in order to properly space the studs or hooks along the edge of the upper. When running a machine at high speed, the operator sometimes fails to advance the work quickly enough after the setting operation to free the set hook or stud from the setting devices before these devices have returned into position to receive the succeeding stud, thus causing delay in the performance of the work and frequently injuring or spoiling the work.

In practicing my invention I insure the removal or freeing of the stud from the setting devices after each setting operation by providing an ejector which engages the set stud and discharges or frees it from the setting device after the setting operation and before the return of the setting devices to position to receive the succeeding stud or before the stud is fed to the setting devices, thus avoiding all danger of an interruption in the proper operation of the feeding and setting devices.

The form, construction, and arrangement of the ejector may be varied to correspond with the specific construction and arrangement of the setting devices and the devices for feeding the hooks or studs thereto without departing from my invention, which consists in the features and combinations hereinafter set forth in the claims.

For the purpose of illustration I have

shown my invention embodied in a hook or stud setting machine in which the hooks are fed to a reciprocating hook-supporting plate, which carries them against a stationary setting-anvil, the setting devices and feeding devices having the same general arrangement as these devices in the machine shown in the patent to W. C. Bray, No. 277,985, May 22, 1883.

So much of this machine as is necessary to illustrate the features of the invention is shown in the accompanying drawings, in which—

Figure 1 is a partial side elevation of the machine. Fig. 2 is a sectional detail of the devices for feeding the hooks to the setting devices. Fig. 3 is a plan view of the hook-supporting plate. Fig. 4 is a detail view of a part of the setting devices, and Figs. 5, 6, and 7 are views showing the setting devices and ejector in the different positions which they assume in the operations of setting the hook and freeing it from the setting devices.

In the machine shown in the drawings the setting devices consist of a stationary anvil A and a hook-supporting plate B, mounted on a vertically-reciprocating plunger B'. The plunger is reciprocated at proper intervals by means of a cam B², engaging one end of a lever B³, the other end of which engages the plunger B', the lever being held in engagement with the cam by means of a spring B⁴, surrounding the plunger.

When the plunger B' is in its lower position, as indicated in Fig. 2, a recess B⁵ in the plate B is in position at the mouth of a guideway C, through which the hooks are fed to the supporting-plate. When the plunger and supporting-plate are in this position, the side B⁶ of the recess B⁵ forms a continuation of one side of the guideway C, while an overhanging lip B⁷ on a block B⁸ forms the continuation of the other side of the guideway. The hook is therefore accurately guided into position on the plate B as it is fed forward by the reciprocating feeding-finger D in the manner fully explained in the patent referred to. As the hook passes on to the plate B the head of the hook passes over a spring-pressed pin B⁹, which serves to retain the hook in position on the plate as the hook is carried

against the anvil A. The block B⁸ is held in fixed position at the mouth of the guideway C by means of a pin B¹⁰, and the plunger B' is provided with a slot B¹¹, in which the block B⁸ plays as the plunger is reciprocated. When the plunger B' is raised, therefore, the plate B is moved away from the upper end of the block B⁸, so that the hook may be freed from the plate by moving it laterally away from the side B⁶ of the recess B⁵.

After the hook has been set as indicated in Fig. 6 the work is spaced or fed forward by the operator as the plunger descends, and this movement must take place before the plunger has descended far enough to bring the head of the hook into the plane of the upper end of the block B⁸, as otherwise the lateral movement of the hook will be prevented or arrested by the block B⁸. In order to insure this lateral movement of the hook before the plunger has descended sufficiently to interfere with its lateral movement, I provide an ejector in the form of a pin E, mounted in the plunger B' and arranged to move under the plate B in a direction to force the head of the hook laterally off the plate. This ejector-pin E is held in retracted position by means of a spring E', which forces the outer end of the pin against the upper end of a lever E². The outward movement of the lever is limited by a shoulder E³, which is engaged by a projection E⁴ on the lever. The lever is mounted in a lug E⁵, secured to the plunger B', and is provided with a projecting arm E⁶, through which it is operated to advance the ejector-pin E at the proper time. The lever is operated by means of an abutment E⁷, arranged in the path of the arm E⁶. This abutment E⁷ is formed on the upper end of an arm E⁸, pivoted to a fixed part of the machine and held in normal position by means of a spring E⁹.

When the parts are in the position shown in Fig. 5, the plate B is in position to receive a hook, the ejector-pin being in its retracted position, so that it does not interfere with the proper feed of the hooks to the supporting-plate. As the plunger rises the arm E⁶ of the lever E² rides against a cam-surface E¹⁰ on the arm E⁸, pressing said arm backward against the tension of its spring until the arm E⁶ passes above the abutment E⁷, when the arm E⁸ is returned to normal position by its spring, as indicated in Fig. 6. After the hook has been set in the material, as indicated in Fig. 6, the plunger B' descends, and as it descends the arm E⁶ rides against the abutment E⁷, rocking the lever E², and thus advancing the ejector-pin E so that it forces the hook laterally off the plate B, as indicated in Fig. 7. As soon as the arm E⁶ passes by the abutment E⁷ the ejector-pin is immediately returned to normal position by its spring ready for the feed of the next hook to the hook-supporting plate.

While I have shown the invention embodied in a machine in which the hooks are fed to a reciprocating supporting-plate and in which the setting-anvil is arranged above the reciprocating plate, it will be understood that the invention may be applied to machines in which the positions of the anvil and plate are reversed or in machines in which either part of the setting devices is a moving part or in machines in which the setting and feeding devices are otherwise constructed and arranged.

What I claim, and desire to secure by Letters Patent, is—

1. A lacing stud or hook setting machine, having in combination hook-setting devices, devices for feeding hooks into position to be operated upon thereby, and an additional device for engaging and freeing the hooks from the setting devices in the direction of the feed after each setting operation.

2. A lacing stud or hook setting machine, having in combination hook-setting devices comprising a hook-supporting plate, a setting-anvil, devices for positioning the hooks on the supporting-plate to register with the setting-anvil, and an additional device for engaging and freeing the hooks from the plate in the direction of the feed after each setting operation.

3. A lacing stud or hook setting machine having in combination, hook-setting devices comprising a hook-supporting plate and setting-anvil, an ejector, and means for advancing and retracting said ejector in the line of the feed between successive setting operations.

4. A lacing stud or hook setting machine having in combination, setting devices comprising a reciprocating hook-supporting plate and setting-anvil, devices for feeding hooks to said plate, an ejector, and means for advancing and retracting the ejector in the line of the feed at each reciprocation of the plate.

5. A lacing stud or hook setting machine having in combination, a setting-anvil, a hook-supporting plate having a recess for the neck of the hook, a guideway for the hooks with which said recess registers, means for reciprocating said plate between the guideway and anvil, and an ejector for forcing the hook off the plate in the direction of the feed after each setting operation.

6. A lacing stud or hook setting machine having in combination, a setting-anvil A, a reciprocating plunger provided with a hook-supporting plate B, an ejector E mounted in the plunger, and means for advancing and retracting the ejector in line with the feed as the plunger reciprocates.

7. A lacing stud or hook setting machine having in combination, a reciprocating plunger provided with a hook-supporting plate B, an ejector E mounted in the plunger, and means for advancing and retracting said

ejector in line with the feed as the plunger is retracted.

8. A lacing stud or hook setting machine having in combination, a reciprocating plunger provided with a hook-supporting plate B, an ejector E mounted therein, a lever carried by the plunger for operating said ejector, and an abutment in the path of the lever for

operating the lever as the plunger is retracted.

In testimony whereof I have affixed my signature in presence of two witnesses.
